UNITED STATES PATENT OFFICE.

JOHN W. JEPSON, OF NEW YORK, N. Y.

ELECTRICAL SYSTEM OF DISTRIBUTION AND REGULATING APPARATUS THEREFOR.

1,233,671.

Specification of Letters Patent. Patented July 17, 1917.

Application filed March 9, 1908. Serial No. 419,993.

To all whom it may concern:

Be it known that I, JOHN W. JEPSON, a citizen of the United States, residing in the borough of Manhattan, New York, New York, have invented certain new and useful Improvements in Electrical Systems of Distribution and Regulating Apparatus Therefor; and in order that those skilled in the art may understand, make, and use my invention I give the following specification thereof.

My invention relates to electrical systems of distribution, and automatic regulating apparatus therefor, and, in the following 15 description and illustration, is shown applicable to lighting circuits, although, as will be readily understood, it is capable of use in connection with circuits for other translating devices. One particular use to 20 which I have contemplated applying my invention is as a voltage regulator for service on lamp circuits on railway cars. One object of the invention is to provide automatically operating apparatus for maintaining a constant potential on the work or 25 load circuit and to maintain said potential constant irrespective of variations in the load or variations of the potential of the generator or battery. A further object is 30 to provide an apparatus which shall perform its functions with a minimum of attention and under the conditions of service such as exist in the lighting of railway cars.

Various other objects, advantages and features will more clearly appear from the detailed description given below.

In the accompanying drawing forming part of the specification I have illustrated diagrammatically a form of my invention 40 applied to a lamp circuit.

In said drawing,

Figure 1 represents a lighting system having my invention applied thereto;

Fig. 2 illustrates a modified form of an 45 element of said system.

Referring to the drawing, the battery is represented by B, which is connected to the lamp circuit L L', having lamps or translating devices W connected across the 50 same. In series between the battery and the lamp circuit is arranged a variable resistance R which consists conveniently of a variable carbon pile resistance in the form of juxtaposed carbon disks or plates c, c, 55 the resistance of which is varied in accordance with the pressure bearing upon said

disks, which pressure is produced by means of an arm A pivoted at X, one end of which bears upon the carbon pile and the other end of which is connected with the core K 60 having a solenoid S² and also preferably a solenoid S¹ acting on the core. Solenoid S¹ is in series with the lamps and solenoid S² is a potential winding across the terminals of battery B. Core K is common to both 65 solenoids and said solenoids are opposed one to the other, the solenoid S¹ tending to retract the core downwardly, in the arrangement shown in the drawing, and solenoid S² tending to retract the core upwardly. 70

An auxiliary or additional regulating means is shown, consisting of a potential coil P across the lamp circuit, coil P acting as a solenoid upon a core F, connected with a lever G, pivoted at D and having its 75 other end bearing upon a carbon pile in series with the solenoid or magnet S², which carbon pile N is of a construction and arrangement similar to the carbon pile forming the variable resistance R. 80

The invention operates in the following manner:

Upon rise of voltage across the battery B, which rise, is consequent upon charging the battery by any suitable source of E. M. 85 F., coil S² receives increased excitation owing to the rise in battery voltage. This increased excitation acts to disturb the equilibrium, causing the core K to move upwardly, thereby relieving the pressure of 90 the arm A upon the carbon pile resistance R and thereby increasing the resistance between the battery and the lamp circuit. The current in coil S¹ will vary with the load on the lamp circuit. If more lamps 95 be switched in circuit, coil S¹ receives increased excitation and tends to pull the core K downwardly, thereby increasing pressure upon the carbon pile resistance R, reducing the resistance in the lamp circuit and permitting the battery to supply additional 100 lamps and counteract the tendency of the lamps to drop in voltage due to increase of load in the lamp circuit, and any lessened excitation of coil S² due to drop in battery 105 voltage will have a tendency to permit the core K to move downwardly, thereby decreasing the resistance at R. If the load on the lamp circuit be diminished by the switching out of a number of lamps, coil 110 S¹ will be affected and core K will have a tendency to move upwardly, tending to in-

crease the resistance in the carbon pile. As a further means of regulation, the coil P which is responsive to the potential in the lamp circuit will, upon a tendency of the potential of the lamp circuit to rise, cause the core F to be moved downwardly, actuating arm G and decreasing the resistance at N, which in turn affects coil S² across the battery, causing it to receive greater excitation and to increase the resistance in the lamp circuit, thereby counteracting the tendency of the lamp circuit potential to rise. Similarly, upon tendency of the lamp circuit potential to drop, core F tends to move upwardly, thereby increasing the resistance of N in series with coil S², and said coil has then a diminished excitation, thereby lessening resistance at R and permitting the voltage in the lamp circuit to rise and counteract any tendency thereof to drop. It will be understood that arms or levers A and G respectively are adjusted by adjusting springs S T with respect to normal conditions in the circuit to cause said arms to exert the proper amount of pressure upon their respective carbon piles to give the proper amount of resistance in the respective circuits required under normal conditions, and that when these normal conditions are disturbed by changes in the load circuit or in the source of E. M. F., said springs S and T will restore their respective arms or levers to normal position upon return of conditions in the circuit to normal.

It will be seen from the above invention that the voltage upon the lamp circuit is automatically maintained constant, irrespective of changes either in battery voltage or in lamp voltage. The addition of the coil P and the resistance N in conjunction with the coils S¹ S² and the variable resistance R permits of very fine regulation.

In the modification shown in Fig. 2 the coil S' is wound about the same core as the coil S² and the two coils are made to oppose one another by oppositely winding or connecting them. This modification therefore operates in much the same manner as already described in connection with Fig. 1.

What I claim is:

1. The combination of supply and lighting circuits and regulating apparatus therefor having in combination a variable resistance in series between said lighting circuit and the supply circuit, means responsive to the potential of the supply circuit and responsive to the load on said lighting circuit for varying said resistance, and means responsive to the potential of the lighting circuit for controlling said first named resistance varying means.

2. In an electrical system of distribution, a source of variable electromotive force, a work circuit fed thereby, a device for regu-

lating the voltage applied to said work circuit, a coil for acting upon said device responsive to fluctuations in the work circuit current, a coil acting upon said device responsive to variations in the voltage of said source, a variable resistance for varying the action of said last mentioned coil and a coil responsive to fluctuations in work circuit voltage for varying the action of said resistance to further vary the action of said device.

3. In an electrical system of distribution, a source of variable electromotive force, a work circuit fed thereby, a variable resistance in series with the work circuit for varying the voltage applied thereto, mechanical means for controlling said resistance, a coil for acting upon said means responsive to current fluctuations in said work circuit, a coil acting upon said means responsive to voltage variations of said source, and a coil for varying the action of said last mentioned coil responsive to voltage variations across said work circuit.

4. Regulating apparatus for work circuits having in combination a carbon pile resistance in series with the work circuit, a movable arm for exerting pressure on said carbon pile for varying its resistance, a coil responsive to the potential of the feeding current for operating said arm to increase the resistance of the pile, and a coil responsive to the potential of the work current for magnifying the operation of said first mentioned coil and resistance.

5. Regulating apparatus for work or lamp circuits having in combination a carbon pile resistance in series with the work circuit, a movable arm for exerting pressure on said carbon pile for varying its resistance, a coil responsive to the potential of the feeding current for operating said arm to increase its resistance, a coil responsive to the current through said resistance for operating said arm for decreasing said resistance, and means responsive to increases in the potential of the lamp circuit for controlling said first mentioned coil to increase said resistance.

6. In an electrical system of distribution, a source of electromotive force, a work circuit fed thereby, a carbon pile resistance for varying the voltage applied to the work circuit, means responsive to variations of work circuit current for acting upon said resistance, means responsive to fluctuations of voltage of said source for also acting upon said resistance and means for varying the action of said last mentioned means responsive to voltage fluctuations of the work circuit.

7. In an electrical system of distribution, a source of electromotive force, a work circuit fed thereby, a carbon pile resistance for varying the voltage applied to the work circuit, means responsive to variations of

- work circuit current for acting upon said resistance, means responsive to fluctuations of voltage of said source for also acting upon said resistance, a carbon pile resistance for varying the action of said last mentioned means and a coil for varying the action of said last mentioned resistance responsive to voltage fluctuations of the work circuit.
8. Regulating apparatus for work circuits having in combination a resistance in series with the work circuit, a coil responsive to the potential of the feeding current for operating to increase the resistance, and a coil responsive to the potential of the work current for magnifying the operation of said first mentioned coil and resistance.
9. The combination of a source of electro-motive force, a work circuit connected thereto, a regulating device for said work circuit, the action of which is varied by the pressure exerted thereon, electromagnetic means for exerting pressure thereon, electromagnetic means for decreasing said pressure and automatic means for controlling the effect said second electromagnetic means have upon the regulating device.
10. A regulating system comprising a generator, and a work circuit, a regulating device for said work circuit, the action of which is varied by pressure exerted thereon, electromagnetic means for exerting pressure thereon, electromagnetic means for decreasing said pressure, and automatic means for governing the operation of said second means.
11. A regulating system comprising a generator and a work circuit, a regulating device for said circuit, the action of which is altered by variations in pressure thereon, electromagnetic means for exerting pressure thereon, electromagnetic means modifying said pressure, and automatic means for controlling said modifying means.
12. A regulating system comprehending a generator and a work circuit, a regulating device for said work circuit, the action of which is altered by variations in pressure thereon, electromagnetic means for exerting pressure thereon, electromagnetic means tending to decrease said pressure, and automatic means for governing one of said electromagnetic means.
13. A regulating system comprising a generator and a work circuit, a regulating device for the work circuit comprising an element the effect of which is altered by variations in pressure thereupon, means for regulating said pressure, comprehending a plurality of windings, and automatic means for determining the current in one of said windings.
14. A regulating system comprising a generator and a work circuit, a work circuit containing translating devices, a regulator for said translating devices, electromagnetic means normally tending to operate said regulator to increase the voltage upon the translating devices, electromagnetic means coöperating therewith to decrease the effect of said last mentioned means, and automatic means for governing the effect of one of the electromagnetic means.

Correction in Letters Patent No. 1,233,671.

It is hereby certified that Letters Patent No. 1,233,671, granted July 17, 1917, upon the application of John W. Jepson, of New York, N. Y., for an improvement in "Electrical Systems of Distribution and Regulating Apparatus Therefor," were erroneously issued to the inventor, said Jepson, whereas said Letters Patent should have been issued to *Gould Coupler Company, a corporation of New York, said corporation being owner, by mesne assignments, of the entire interest in said invention* as shown by the record of assignments in this office; and that the said Letters Patent should be read with this correction therein that the same may conform to the record of the case in the Patent Office.

Signed and sealed this 2d day of October, A. D., 1917.

[SEAL.]

F. W. H. CLAY,

Acting Commissioner of Patents.
